DIE HEAD

Ralph E. Hyde, Cleveland, Ohio, assignor to The Oster Manufacturing Company, Cleveland, Ohio, a Corporation of Ohio

Application February 28, 1931. Serial No. 519,093

4 Claims. (Cl. 10—96)

The present invention relates to a die-head, and particularly to a die-head of the general type disclosed in the patent to Oster No. 1,044,808.

5 Among the objects of the present invention are to provide a die-head of the character described which has improved features making for increased accuracy, efficiency and readiness of application and removal. Another object is the 10 provision of a die-head particularly adapted for use on a rotating machine, particularly of the semi-automatic or automatic type.

Further objects of the invention will appear from the following description.

15 It is to be understood that the description and the accompanying drawings are illustrative of preferred means of accomplishing the purposes of the invention, but that these are to be taken as examples and not as limitations. The invention 20 is capable of being applied in a variety of mechanical forms, the inventive scope being indicated by the claims.

In the drawings, Fig. 1 is a front elevation of the improved die-head, certain features being 25 omitted for the sake of simplicity; Fig. 2 is a central vertical longitudinal section through the die-head, the back plate being omitted; Fig. 3 illustrates a detail of the adjusting means; Fig. 4 is a perspective view of the chaser pin shown 30 in Fig. 2; Fig. 5 illustrates a cam slot used in the shifter ring; Fig. 6 is a front view corresponding to Fig. 1 but illustrating a modified construction; Fig. 7 is a view on the line 7—7 of Fig. 6; Fig. 8 is a partial front view looking in the direction of the arrow 8, Fig. 7, showing a front 35 view of the setting means on a larger scale; Fig. 9 is a section through the shifter ring on the line 9—9 of Fig. 7; and Fig. 10 is a partial plan view also on the line 9—9 of Fig. 7 but with the shifter 40 ring removed and part of the die carrier broken away.

Referring now to Figs. 1, 2 and 3, the apparatus is seen to consist of a die-head 1 having a tubular die carrier 2 through which the pipe or other cylindrical work to be threaded passes in the usual manner. This die carrier has a flange-like enlargement 3 at the rear within suitable recesses 4 of which chasers 5 are carried, being movable on radial lines by the action of spiral cam grooves 6 which engage pins 7 on the chasers to move the latter. The pins 7, as best shown in Fig. 4, consist of a cylindrical shank 7^A, a short enlarged cylindrical head 7^B concentric upon one end of the shank, and a guide fin 7^C curved on the radius of the slots 6 and of proper thickness

to slide in the slots. The shank 7^A fits snugly in a hole 6' in the rear edge of the chaser body 5, as shown in Fig. 2. The chasers 5 are here shown as fitted with detachable cutter blades 5'. The grooves 6 are formed in an annular cam plate 8 mounted on the outer surface of the die carrier 2, concentric therewith, and engaging against annular rabbets in the rear face of the flange-like member 3. This cam plate 8 is kept from sliding rearwardly by a flat ring 9 suitably fastened to the rear outer edge of the outlet 3. It will thus be seen that the plate 8 is capable of rotation around the die carrier 2, but not of translation therealong. An arcuate plate 10 is fitted by a ridge and groove 11, or other suitable arrangement, concentric with the cam plate 8, to a portion of the cam plate 8, being secured thereto by means of a nut 12 and stud 12'. An arcuate slot 13, also concentric with the cam plate, permits relative movement between the plates 10 and 8, any particular setting being held by tightening the nut 12. Suitable index marks such as 14 on the plates 8 and 10 permit any predetermined setting between these plates to be quickly and accurately made.

The plate 10 is of L shaped cross section as seen in Fig. 2, with the foot of the L extending a short distance above the top of the die carrier 2, but separated therefrom by a flat shifter ring 15. A cam groove 16 extends diagonally through the under face of the plate 10 changing to an axial direction for a short distance near the front end as shown at 17, Fig. 5, to prevent rotation of the cam plate when the chasers are closed. This groove is entered by the upper end 80 of a stud 18 rigid in the front portion of the ring 15. The stud and groove may conveniently have a ball-and-notch detent to maintain the organization in position, all as indicated in Fig. 2.

The shifter ring 15 is keyed on the outside of 95 the carrier 2, thus being movable axially but not circumferentially of the carrier, thus moving the stud 18 circumferentially a distance equal to the circumferential component of the groove 16, and 100 so opening or closing the chasers.

To move the ring 15 axially along the die carrier 2, any suitable mechanism may be provided. A convenient arrangement is a shifter yoke, indicated in Fig. 2 by the trunnions 19 engaging a 105 circumferential groove, as shown, in the ring 15, and yoke arms 20. By this arrangement the chasers may be moved from their inmost to their outmost position in any given setting without it being necessary to stop the rotation of the die- 110

head. Of course changes in adjustment can be made only when the head is stationary.

- The die-head of Figs. 1 and 2 is shown as fitted with a known form of cut-off mechanism, consisting of a cutter 21 carried in an internally threaded sleeve 22 and movable upward slowly by a threaded shaft 23 working in the internal threads of the sleeve and bearing against a block 24 in the outer portion of the flange element 3. 5 A star wheel 25 is rigidly fastened to an extension 26 of the shaft 23, which star wheel is turned step by step by suitable mechanism, not shown. The above mechanism is a usual attachment for die heads and is not in itself a feature of the 10 present invention.

- With reference to Figs. 6 to 10 inclusive, the apparatus may be modified to comprise a tubular die carrier 32 having a ring-shaped cam plate 33 mounted upon the front end of 32 and concentrically with respect to the axis of the opening through 32. This cam is being held in place by an annular cover plate 34. The cover plate includes four quadrantly placed radial channels 35 which form guides for the chasers 36. 20 Inwardly directed arcuate fins 37 are formed on the front face of the cam plate 33 and engage slots 38 in the rear edges of the chasers, whereby rotation of the cam plate moves the chasers in and out radially. 25 Rotation of the cam plate is accomplished by a stud 40 upstanding from an arcuate plate 41 which is secured by a bolt 42, clamping bushing 43 and nut 44 to the cam ring 33. The plate 41 has a ridge and groove sliding contact with the 30 cam ring 33 and may be moved circumferentially with respect therewith when the clamping elements 43 and 44 are loosened. The extent of this travel is governed by the length of an arcuate slot 45 in the plate 41, the relationship being substantially the same as that existing between the 35 cam ring 8 and the plate 10 in Fig. 2.

- The upstanding stud 40 projects through a slot 46 in the outer surface 47 of the die carrier 32, the die carrier being suitably enlarged as shown 45 in the upper part of Fig. 2 to receive the adjusting mechanism just described. The clamping bushing 43 has an enlarged head 48 which is level at the top with the outer rear surface 47. This head 48 carries an index mark 49, Fig. 10, which 50 may be brought opposite any one of a series of graduations 50 on the upper surface 47. When the ring 52 is moved to the right in Fig. 7, the 55 graduations 50 are exposed.

- Motion of the cam plate to move the chasers 55 in or out after any desired adjustment has been set, is accomplished by a shifter ring 52 movable axially along the die carrier 32 but keyed thereto as at 53 preventing relative rotation. This shifter ring is inwardly grooved 60 diagonally as at 54, the groove 54 having a short axially directed section 55 at one end, into which groove the stud 40 projects. Axial movement of the ring 52 thus causes a limited circumferential movement of the stud 40 thus moving the cam plate. The stud 40 may conveniently be provided with a ball-and-spring detent cooperating with a notch in the axial section 55 of the groove, so as to hold the apparatus in closed 65 position. 70 It will be seen from the foregoing that in either form of the apparatus range within which the chasers move between open and closed position is governed by the setting of a relatively short arcuate plate which may be secured to the cam plate 75 at any point within its range of adjustment and

that the movement of a shifter yoke opens or closes the chasers within the predetermined setting limits. By the use of a ring type of shifter yoke it is possible to open or close the chasers while the entire assembly is rotating so that these forms of head are particularly adapted to semi-automatic or automatic machines, it being necessary to stop the machine only for changes in adjustment. 80

It will be understood that the scope of the invention is not limited to the two forms herein shown and described but that the principles may be embodied in other mechanisms, the scope of the invention being determined by the following claims. 85

What I claim is:

1. In combination with a die head, a longitudinally disposed body, an annular cover plate on one end of said body, radially disposed hollow ribs on said cover plate, chasers reciprocably mounted within said ribs, cam engaging elements in said chasers, a cam ring mounted rotatably within the limits of said body and behind said cover plate, means for preventing axial motion of said cam ring, a concentric arcuate plate 100 mounted on said cam ring, means for selectively clamping said arcuate plate fast to said cam ring or for permitting relative circumferential motion between the two, a shifter ring mounted upon and between the ends of said longitudinal body, key connections between said longitudinal body and said shifter ring permitting axial but preventing circumferential relative motion between the two, cam connections between said arcuate plate and said shifter ring, said cam connections 105 having both axial and circumferential components. 110

2. A die head comprising in combination a laterally extending body, an annular cam plate mounted adjacent one end thereof, chasers mounted radially in one end thereof, and cam-and-slot connections between said chasers and said cam plate, said connections comprising a pin seated in one edge of said chaser and a head on said pin projecting from said chaser, said head 115 including enlarged flat bearing surfaces against the inner face of said cam plate and the edge of said chaser opposite thereto, respectively, and a projecting arcuate fin having side cam surfaces 120 corresponding to the cam surfaces on said cam ring slot. 125

3. A die head comprising in combination a tubular body, a rotatable cam plate within the axial dimension of said body, chasers radially movable by said cam plate, a radial projection 130 upon said cam plate through the side of said body, and a shifter ring surrounding said body axially movable thereon but not therebeyond, an inward cam groove on said ring engaging with said radial projection, whereby movement of said 135 ring axially rotates said cam plate.

4. A die head comprising in combination a tubular body, a rotatable cam plate within the axial dimension of said body, chasers radially movable by said cam plate, a radial projection upon said cam plate through the side of said body, means carried by said cam plate housed within and projecting axially rearwardly of said body for adjusting said radial projection, and a shifter ring surrounding said body axially movable thereon but not therebeyond, an inward cam groove on said ring engaging with said radial projection, whereby movement of said ring axially rotates said cam plate. 145
